(57) **CLAIM**

The ornamental design for a table for building block toys, as shown and described.

DESCRIPTION

FIG. 1 is a front, top and right perspective view of a table for building block toys showing our new design;

FIG. 2 is a front, bottom and left perspective view thereof;

FIG. 3 is a front view thereof, a rear view being a mirror image of the front view;

FIG. 4 is a left side view thereof, a right side view being a mirror image of the left view;

FIG. 5 is a top view thereof;

FIG. 6 is a bottom view thereof; and,

FIG. 7 is a partially enlarged view showing the area "7" in FIG. 1.

The even broken lines depict portions of the table for building block toys that form no part of the claimed design. The dot-dash broken lines indicating an enlargement portion of the design form no part of the claimed design.
